James E. Grace,
INVENTOR

BY Victor J. Evans
ATTORNEY

Fred W. Ely,
WITNESS:

UNITED STATES PATENT OFFICE.

JAMES E. GRACE, OF NEW YORK, N. Y.

CLIP.

Application filed August 23, 1921. Serial No. 494,618.

To all whom it may concern:

Be it known that I, JAMES E. GRACE, a citizen of the United States, residing at New York city, in the county of Bronx and 5 State of New York, have invented new and useful Improvements in Clips, of which the following is a specification.

This invention relates to clips and in many respects is an improvement on the device 10 shown in my Patent Number 1,177,511.

The principal object of the device is to facilitate the operation of attaching tags to packages for parcel post and like purposes and to files and other objects in office and 15 store use.

Another object is to produce a clip whereby the tag may be readily attached to a package without the free ends of the clip protruding in such manner that the hands of 20 the mail carrier or other handler can be injured thereby. This feature is to conform with the requirements of the U. S. Post Service that clips shall not be used which could in any way injure the carrier or clerk.

With these and other objects in view the invention resides in certain novel construction, the essential features of which are hereinafter fully described, are particularly pointed out in the appended claims, 25 and are illustrated in the accompanying drawing, in which:—

Figure 1 is an enlarged perspective view of my improved clip per se.

Figure 2 is a view showing the manner of 35 attaching the clip to the string of a package.

Figure 3 is a similar view showing the clip attached to the string and the tag in the process of being attached.

Figure 4 is a view of the package tag and 40 clip in the final attached form.

Like characters of reference refer to like parts in all views.

Referring to the drawing in detail, 10 45 represents a package, 11 represents a cord thereon and 12 represents a tag to be attached thereto.

The clip per se is made from a single length of wire 13 having its opposite ends bent angularly into legs 14. Each of the 50 legs 14 has its free end doubled upon itself at 15 so as to form a return portion 16

which extends substantially parallel with its respective leg 14. The points of bend 15 are in the normal condition superposed as shown 55 in Figure 1.

In use the clip is first slipped onto a string of the package in the manner shown in Figure 2 so that the string lies in the triangular opening defined by the clip. The 60 aperture 17 of the tag 12 is then placed over the points 15 and pressed against the portions 16 forcing the same to cross each other and permit the tag to slip over the ends of the elements 16. The springiness of legs 14 65 then causes the members 1 and 16 to return to normal condition with the bends 15 in superposed relation, the legs 14 on one side of the tag 12 and the portions 16 on the other side. The tag is then pulled down- 70 wardly so that the margins of the aperture 17 is forced downwardly into the bends 15 thereby drawing the legs 14 apart and forcing them into substantially the same plane, the portions 16 pressing tightly against the 75 card and lying also substantially in the same plane as the legs 14 and in protected condition thereagainst, so that there is no danger to the clerk handling the package.

What is claimed as new is:—

1. A clip having legs formed and bent to provide V-shaped parts which lie normally side by side with the apexes thereof coinciding to constitute a point for insertion in the eye of a shipping tag, whereby on pulling 85 the clip, the legs thereof will be separated to dispose the V-shaped parts respectively at the sides of the eye.

2. A clip formed and bent from a single piece of material to provide legs on a central part, V-shaped parts on the free ends of the legs, the said V-shaped parts lying normally side by side with the apexes thereof coinciding to constitute a point for insertion in the eye of a shipping tag, whereby on pulling 90 the clip, the legs thereof will be separated to dispose the V-shaped parts respectively at the sides of the eye.

3. A clip formed and bent from a single piece of springy material to provide legs on a central part, a V-shaped part at the end of each leg, the said V-shaped parts lying normally side by side with the apexes thereof coinciding, to constitute a point for insertion 100

in the eye of a shipping tag, whereby on pulling the clip, the legs thereof will be separated to dispose the V-shaped parts respectively at the sides of the eye.

5. A clip having legs formed with V-shaped parts which lie normally one on top of another with the apexes thereof coinciding so as to normally constitute a point in line with the longitudinal axis of the clip

and adapted to be passed through an eye of a shipping tag and arranged, whereby the legs may be separated relatively and spread beyond the sides of the eye after the clip is inserted and upon the exertion of pull upon the clip. 10

In testimony whereof I have affixed my signature.

JAMES E. GRACE.
